CLAIM

The ornamental design for a sofa, chair and table set, as shown and described.

DESCRIPTION

FIG. 1 is a top, front and left side perspective view of a sofa, chair and table set, showing our new design;

FIG. 2 is a bottom, rear and left side perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a left side elevational view thereof;

FIG. 8 is a right side elevational view thereof; and,

FIG. 9 is another front, top and left side perspective view of the sofa, chair and table set with two armchairs.

The broken lines in the figures depict environmental subject matters and form no part of the claimed design.
